UNITED STATES PATENT OFFICE.

WILKENS A. SCHENCK, OF PHILADELPHIA, PENNSYLVANIA.

DRAWING INSTRUMENT.

1,292,086.

Specification of Letters Patent.

Patented Jan. 21, 1919.

Application filed April 12, 1918. Serial No. 228,224.

To all whom it may concern:

Be it known that I, WILKENS A. SCHENCK, a citizen of United States, residing at 44 N. Fourth street, Philadelphia, in the county of Philadelphia and State of Pennsylvania, have invented new and useful Improvements in Drawing Instruments, of which the following is a specification.

The invention relates to drawing instruments, and more particularly to dividers or compasses, and has for an object to provide a drawing instrument that can be cheaply constructed, will consist of few parts that cannot readily become broken or accidentally disassembled, the instrument being designed with a view to providing a strong, durable article that can be used for all kinds of work to which instruments of this character are adapted, and which on account of its simplicity, and the formation of various parts, can be cheaply marketed.

Among other features, the invention comprehends a drawing instrument in which the legs and other parts are preferably made of stamped metal with a suitable self-centering head, if desired, that will enable the user to effectively employ the instrument for the purpose intended. Further, the invention comprehends a drawing instrument in which the parts after being made, can be quickly and readily assembled without the requirement of skilled labor, and to this end the stamped metal and other parts are made to readily interfit, and thereby form an instrument that will have a neat and effective appearance.

In the further disclosure of the invention, reference is to be had to the accompanying drawings, constituting a part of this specification, in which similar characters of reference denote corresponding parts in all the views, and in which—

Figure 1 is a side elevation of the instrument.

Fig. 2 is an end elevation.

Fig. 3 is a vertical longitudinal sectional view of the instrument as shown in Fig. 1, and taken on the line 3—3 in Fig. 2.

Fig. 4 is a vertical longitudinal sectional

view of the instrument taken on the line 4—4 50 in Fig. 1.

Fig. 5 is a horizontal sectional view taken on the line 5—5 in Fig. 1.

Fig. 6 is a horizontal sectional view taken on the line 6—6 in Fig. 1, and 55

Fig. 7 is a detail perspective view of one of the point-holding elements.

Referring more particularly to the views, the instrument in its entirety is indicated by the numeral 10, and is made up primarily of 60 a plurality of legs 11, 12, each formed of a single piece of stamped metal, which in cross section is U-shaped, thus providing great strength, it being readily understood that the legs can be readily stamped out 65 from a single sheet of material and thus lower the cost of production. The upper end of the leg 11 is formed with a bearing head 13, and the upper end of the leg 12 is similarly formed with a bearing head 14. 70

A knob or holder 15 has suitably secured thereon an inverted U-shaped yoke 16 which passes around the bearing heads 13, 14 as shown, and between the bearing heads there is disposed a ball-bearing disk 17 provided 75 with a plurality of openings 18 in which are disposed balls 19, said balls projecting from each side of the disk through the openings 18, to bear against the inner faces of the bearing heads 13, 14, a screw 20 being 80 arranged to pass through one of the sides of the yoke 16 and then through the bearing head 13 and disk 17, and thence through the other bearing head 14 on the other side 85 of the yoke 16. Thus the legs 11, 12 will be pivoted at their upper ends and can readily be separated, due to the ball-bearing action of the balls 19. In order to maintain the handle or knob 15 in an upright position, the disk 17 is formed with projections 20 90

providing a grooved portion 21, and by reference to the views it will be seen that the central portion of the yoke 16 extends between the projections 20 and lies in the grooved portion 21, so that regardless of 95 the manner in which the legs 11, 12 are manipulated by separation, or by moving them together, the holder or knob 15 will

always maintain an upright position, thus providing what may be termed a self-centering head.

The leg 11 is made shorter than the leg 12 and at a distance from its lower portion which I term a tongue or extension 22 of the leg, there is disposed in the grooved portion of the leg a socket element 23 which is held in place by a screw 24, passing through the leg and the socket. The socket element 23 has a tongue 25 projecting therefrom in spaced relation to the tongue 22, so that the upper end of a supplementary leg 26, formed with a tongued portion 27 riveted to the leg 26, can be engaged with the leg 12 by having the tongued portion 27 fitting between the tongue 25 and the tongue 22 of the leg 12, after which the screw 24 is tightened to rigidly clamp the tongued portion 27 and the supplementary leg 26 to the leg 12. The upper end of the supplementary leg 26, fitting into the grooved part of the leg 12, will thus be securely held in clamped position, although the same can be readily removed by unloosening the screw 24.

Movably attached to the lower end of the leg 12 and supplementary leg 26 are point-holding devices 28, one being provided for each leg. Each point-holding device in detail consists of a U-shaped plate 29 having a transverse aperture 30 through which passes a screw 31, which also passes through a transverse aperture 32 in the lower part of the leg, the plate 29 being of a spring-like nature so that a point 33 can be readily clamped therein, whereupon when the plate 29 is arranged between bifurcated portions 34 of the leg 11 and supplementary leg 26, and the screw 31 tightened up in each instance, the plate will be clamped rigidly, and the point 33 will also be clamped in the plate. With this arrangement the point-holding devices can be swung at angles to the legs to which they are attached, as will be readily seen by referring to the views. Attention is called to a notch 35 in each plate which with a projecting lip 36 forms a finger hold, enabling the user to readily swing the point-holding devices relative to the legs to which they are attached, when the screw 31 is loosened.

From the foregoing description it will be seen that the device consists of few and simple parts, that can be readily and cheaply assembled, and that by reason of the main parts of the device being made of stamped metal, it will be clear that the article described can be very cheaply marketed, and at the same time will form an effective instrument for the particular use to which it is adapted by reason of the added strength that is obtained in the manufacture of the device by having the legs when stamped out, U-shaped in cross section.

Although I have shown a particular form

of my invention in the drawings, it will be understood that I do not limit myself to the arrangements set forth; that various slight changes may be made from the spirit of the invention without departing from the scope thereof, the latter being defined in the appended claims.

I claim:

1. An article of the character described, comprising a plurality of main legs, U-shaped in cross section, means at the upper ends of the legs for relatively pivoting the same, a socket member disposed in the U-shaped portion of one of the main legs, a supplementary leg, a tongue in the supplementary leg and interfitting with the socket member in the main leg and the U-shaped portion thereof, and means for clamping said U-shaped portion and said socket member to said tongue. 75

2. An article of the character described, comprising a plurality of main legs, U-shaped in cross section, means at the upper ends of the legs for relatively pivoting the same, a socket member disposed in the U-shaped portion of one of the main legs, a supplementary leg, a tongue in the supplementary leg and interfitting with the socket member in the main leg and the U-shaped portion thereof, means for clamping said U-shaped portion and said socket member to said tongue, point-holding devices swiveled on the lower end of one of the main legs and on the supplementary leg, and means for clamping the same rigidly thereto. 90

3. An article of the character described, comprising a plurality of legs, U-shaped in cross section, a bearing head on the upper end of one leg, a bearing head on the upper end of the other leg, a ball-bearing disk interposed between said bearing heads, a knob, a yoke on the knob and straddling said disk and bearing heads, a pin connecting the yoke, said bearing heads and said disk, and forming a notch therein with the yoke passing through the notch, and a supplementary leg for attachment to said other leg and fitting into the U-shaped portion thereof. 105

4. An article of the character described, comprising a plurality of legs, U-shaped in cross section, a bearing head on the upper end of one leg, a bearing head on the upper end of the other leg, a ball-bearing disk interposed between said bearing heads, a knob, a yoke on the knob and straddling said disk and bearing heads, a pin connecting the yoke, said bearing heads and said disk, and forming a notch therein, with the yoke passing through the notch, a supplementary leg for attachment to said other leg and fitting into the U-shaped portion thereof, and point-holding devices on the lower end of the first-mentioned leg and on the supplementary leg and held between bifurcated portions thereof. 110 120 125

5. In combination with the legs of a drawing instrument, said legs being bifurcated at their lower ends, point-holding devices, each formed of a single piece of U-shaped material, said point-holding devices fitting between the bifurcated portions of said legs, fastening elements clamping said point-holding devices between bifurcated portions

of said legs, and clamping the points in said point-holding devices, and finger grips on 10 said point-holding devices for adjusting the same to different angles relative to the legs to which they are attached.

In testimony whereof I affix my signature.

WILKENS A. SCHENCK.
